(57) **CLAIM**

The ornamental design for a bedside table, as shown and described.

DESCRIPTION

FIG. 1 is a front, right, top perspective view of the first embodiment of a bedside table, showing my new design; FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, top perspective view of the second embodiment of a bedside table, showing my new design; FIG. 10 is a rear, left, bottom perspective view thereof;

FIG. 11 is a front elevational view thereof;

FIG. 12 is a rear elevational view thereof;

FIG. 13 is a left side view thereof;

FIG. 14 is a right side view thereof;

FIG. 15 is a top plan view thereof;

FIG. 16 is a bottom plan view thereof;

FIG. 17 is a front, right, top perspective view of the third embodiment of a bedside table, showing my new design; FIG. 18 is a rear, left, bottom perspective view thereof;

FIG. 19 is a front elevational view thereof;

FIG. 20 is a rear elevational view thereof;

FIG. 21 is a left side view thereof;

FIG. 22 is a right side view thereof;

FIG. 23 is a top plan view thereof;

FIG. 24 is a bottom plan view thereof;

FIG. 25 is a front, right, top perspective view of the fourth embodiment of a bedside table, showing my new design; FIG. 26 is a rear, left, bottom perspective view thereof;

FIG. 27 is a front elevational view thereof;

FIG. 28 is a rear elevational view thereof;

FIG. 29 is a left side view thereof;

FIG. 30 is a right side view thereof;

FIG. 31 is a top plan view thereof; and,

FIG. 32 is a bottom plan view thereof.

(Continued)

The dashed broken lines in the figures are for the purposes of illustrating portions of the bedside table that form no part of the claimed design.
